UNITED STATES PATENT OFFICE.

PAUL KRÜGER, OF ESSEN, GERMANY, ASSIGNOR TO FRIED. KRUPP AKTIENGESELLSCHAFT, OF ESSEN-ON-THE-RUHR, GERMANY.

SELF-DISCHARGER.

Application filed October 14, 1921. Serial No. 507,734.

To all whom it may concern:

Be it known that I, PAUL KRÜGER, residing at Essen, Germany, a citizen of the German Republic, have invented a certain new and useful Improvement in Self-Dischargers, of which the following is a specification.

The present invention relates to self-dischargers with a bottom which can be tilted towards both sides, overcoming the action of a spring in the operation; and the object of 10 the invention is to simplify this construction of self-discharger.

The invention will be described with reference to the accompanying drawings which 15 show an example of the invention as applied to a self-discharger.

Figure 1 is a schematic view of a transverse section through the receptacle when in the loading position.

20 Figure 2 is a section of the receptacle corresponding to Figure 1 after discharge has taken place to one side; and

Figure 3 is a section of the receptacle corresponding to Figure 1 after discharge has 25 taken place to the other side.

On the underframe A of the receptacle, such as a car or the like, are rigidly mounted parallel with each other the two end walls A¹. There are also mounted on the under 30 frame A at the front and rear ends of the receptacle, two bearing brackets A² each of which lies symmetrical with the central longitudinal plane of the receptacle. These bearing brackets are provided for the reception of two shafts B running right through and on which are mounted in pairs, oppositely situated crank arms b¹. These cranks b¹ are connected to the bottom C of the receptacle by a connecting rod D in each case.

40 On the under frame A are also provided stops a³ which, when the crank arms bear against them, permit the latter to rotate in an inward direction only. On the bottom of the receptacle are provided stops c¹ for the 45 connecting rods D which likewise permit the latter to rotate in an inward direction only. Operating levers H connected to the shafts B are provided for rotating the said shafts to initiate the tilting movement of the bottom C.

Each of the two side walls of the receptacle F is provided on its lower edge with bearings f¹ which are open underneath and which when the receptacle is ready to be 55 loaded engage with pins c² on the bottom C

and rests at its upper edge in open bearings a⁴ on the end walls A¹ (see Figures 2 and 3). The side walls F are guided by connecting rods G which are mounted on the end walls A¹.

The crank arms b¹ are prolonged by a piece b² beyond their axis of rotation and connected in pairs with each other by a coiled spring E which is attached to the prolonged parts b² and under the action of which spring the crank arms bear against the stops a³.

When the receptacle is to be discharged to one side e. g. towards the right (see Figure 2) the crank arms b¹ situated on the right hand side of the central longitudinal plane are turned inwards slightly by rotating the appurtenant shaft B by means of the operating lever H in the direction of the arrow x. Under the action of the weight of the material contained in the receptacle the bottom then tilts automatically towards the right, turning on the hinges which connect the crank arms b¹ situated on the left and remaining at rest with the connecting rods D 80 belonging thereto and bearing against the stops a³ and therefore moving with the bottom.

By the tilting of the bottom the springs E lying between the prolonged parts b² of the 85 crank arms b¹ are stretched to the right so that a portion of the mechanical work which is released when the bottom moves over into the discharge position, is stored up in them. On the return of the bottom C to the loading 90 position the crank arms b¹ lying on the right hand side of the central longitudinal plane of the receptacle are rotated back into their original position in the opposite direction to that indicated by the arrow x. The 95 result of this movement of the crank arms is, that the bottom C of the self-discharger is also rotated back into its original position, by which operation an amount of work which is dependent on the ratios of 100 the weight of the movable parts particularly the bottom, has to be done. In this return movement to the loading position the springs E contract and give up again the mechanical work stored up therein, so that 105 only a small expenditure of force is necessary for the operation of the crank arms b¹ which is effected by hand.

The discharge of the receptacle towards the left (see Figure 3) requires no special 110

explanation, as the operations correspond exactly to those which take place on the discharge of the receptacle to the right. It need only be mentioned that in this case (contrary to the first one) the crank arms on the right remain at rest and the coiled springs E are stretched towards the left.

It is naturally not important to the present invention that the members which are connected in pairs by a coiled spring E should be constituted by crank arms (b¹ b²). The only important point is, that they be two members which (in the well known way) are so movable relatively to each other both on the tilting movement of the bottom towards one side as well as the other, that the distance between two points of these members always alters in the same direction and that therefore a spring attached at these two points will always have the strain put upon it in the same manner i. e. it will always be either compressed or stretched.

This secures the advantage that by means of a single spring the same advantage can now be secured as was formerly obtained with two springs which constitutes a considerable simplification of the construction.

I claim:—

1. In a self-discharging receptacle provided with a bottom tiltable towards both

sides, a pair of members movable relatively to each other on the tilting movement of the bottom, whereby the distance between the ends of said members varies in positive dependence on the movement of the bottom and a spring connecting the said ends of said members and tensioned by the mutual movement of said members.

2. In a self-discharging receptacle provided with a bottom tiltable toward both sides, two members pivotally mounted and movable relatively to each other on the tilting movement of the bottom, the distance between the ends of said members varying in positive dependence on the movement of the bottom and a coiled spring interposed between said members and connected to the said ends thereof and tensioned by the mutual movement of the said members.

3. In a self-discharging receptacle provided with a bottom tiltable toward both sides, crank arms pivotally mounted on the underframe of the receptacle on both sides of the central longitudinal plane of the receptacle, connecting rods movable in one direction relatively to said bottom for connecting said crank arms to said bottom, extensions on said crank arms and a coiled spring connecting said extensions.

PAUL KRÜGER.
